(57) **CLAIM**

The ornamental design for a container for spraying, as shown and described.

DESCRIPTION

FIG. 1 is a perspective view with the cap on of a container for spraying of the present invention.

FIG. 2 is a top plan view with the cap on of the container for spraying of FIG. 1.

FIG. 3 is a front view with the cap on of the container for spraying of FIG. 1.

FIG. 4 is a right side view with the cap on of the container for spraying of FIG. 1.

FIG. 5 is a bottom view with the cap on of the container for spraying of FIG. 1.

FIG. 6 is a rear view with the cap on of the container for spraying of FIG. 1.

FIG. 7 is a left side view with the cap on of the container for spraying of FIG. 1.

FIG. 8 is a perspective view with the cap off of the container for spraying of FIG. 1.

FIG. 9 is a top plan view with the cap off of the container for spraying of FIG. 1.

FIG. 10 is a front view with the cap off of the container for spraying of FIG. 1.

FIG. 11 is a right side view with the cap off of the container for spraying of FIG. 1.

FIG. 12 is a bottom view with the cap off of the container for spraying of FIG. 1.

FIG. 13 is a rear view with the cap off of the container for spraying of FIG. 1; and,

FIG. 14 is a left side view with the cap off of the container for spraying of FIG. 1.
